ART OF MAKING SHOES

Anthony Cocozella, Lynn, Mass.

Application November 28, 1933, Serial No. 700,071

16 Claims. (Cl. 12—142)

The present invention relates to the art of making shoes.

Experience has demonstrated that the use in the shoe industry of adhesives to secure permanently the lasted upper to the insole, and the outsole to the lasted shoe, produces a very stiff shoe, much less flexible than the McKay shoe. The realization of this has proved disappointing to the manufacturers that have committed themselves definitely to the use of adhesives, particularly those that make shoes for women, who generally demand flexible shoes. In my application, Serial No. 665,663, filed April 12, 1933, I have disclosed a shoe which is flexible notwithstanding the fact that in its manufacture adhesives may be used to secure permanently the lasted upper to the insole and the outsole to the lasted shoe.

The principal object of the present invention is to improve the flexibility of the type of shoe disclosed in my application hereinbefore identified.

To the accomplishment of this object, and such others as may appear hereinafter, the various features of the present invention reside in certain shoe constructions and certain processes of manufacture hereinafter described and then pointed out broadly and in detail in the appended claims, possessing advantages readily apparent to those skilled in the art.

The various features of the present invention will be understood readily from an inspection of the accompanying drawing, illustrating the best form of the invention at present devised, in which,

Figure 1 is a view in elevation of a woman's pump;

Fig. 2. is a view in bottom plan of the lasted shoe;

Fig. 3 is an enlarged view in sectional elevation on the line 3—3, Fig. 1;

Fig. 4 is a view in plan of the sponge-rubber pad, and

Fig. 5 is a view in sectional elevation on the line 5—5, Fig. 4.

Referring to Fig. 2, after the lasting operation, the lasted shoe comprises an upper 6, (which term is used herein to include the lining materials), which is secured in overdrawn position to the lasting flange of an insole 7 mounted on the bottom of a last 8. The forepart of the insole is provided with an opening 9 through which the bottom of the last 8 may be observed.

Preferably the margin of the upper around the

forepart of the lasted shoe is trimmed to the edge of the aperture 9.

The opening 9 may be formed in the forepart of the insole either before or after the lasting operation. Preferably, however, the opening 9 is formed in the forepart of the insole in the manner disclosed in my application Serial No. 665,663, filed April 12, 1933.

The overdrawn margin of the upper may be secured to the lasting flange of the insole by any of the well known mediums, such as tacks, thread or staples. Preferably, the overdrawn margin of the upper is secured to the lasting flange of the insole by an adhesive. This adhesive may be of the type which permanently secures the overdrawn upper to the lasting flange of the insole. Preferably, the adhesive is treated to retain its adhesive property temporarily. That is, the adhesive is not designed to unite the components of the lasted shoe permanently. The adhesive is sufficient merely to secure the margin of the upper in its desirable lasted position to the insole during the subsequent shoe making operations.

After the upper and insole have been brought into the condition illustrated in Fig. 2, the vertical wall of the opening 9 and the adjacent margin of the overdrawn upper are provided with adhesives. Over the opening 9 is placed a cover 10 (Fig. 3) which is died out of some thin material such as a split or leather of the type used for uppers. The cover 10 is died out to a size larger than the opening 9 so that after it has been positioned thereover in contact with substantially the entire surface of the overdrawn upper surrounding the opening 9, the cover may be tucked down into engagement with the cemented vertical wall of the opening and secured thereto. During this tucking operation a portion of one face 11 of the cover 10 is spread smoothly over the bottom of the last 8 thus insuring the positioning of the face 11 of the cover substantially flush with that face of the insole which is exposed to view in the finished shoe or to which in some shoes there is secured a lining (not shown) which engages the sole portion of the sock of the wearer. The adhesive applied to the vertical wall of the opening 9 is designed to secure the cover 10 permanently thereto. The adhesive applied to the margin of the overdrawn upper adjacent the opening 9 is designed to secure the cover 10 temporarily thereto.

When the cover 10 is secured in position as shown in Fig. 3 it forms a cup (Fig. 3) in which is

placed a died out piece of sponge-rubber 12 (Figs. 4 and 5). The sponge rubber 12, which is perforated, is died out from a sheet to a size, somewhat smaller than the opening 9, so that it does not completely fill the cup formed by the cover 10. One face of the sponge-rubber pad 12 may be secured to the face 13 of the cover 10 opposite its face 11.

Then the outsole 14 is placed in position over the bottom of the lasted shoe and secured thereto by an adhesive, care being taken to prevent the outsole from being coated with adhesive in that portion adjacent the pad 12. Preferably, the adhesive employed to secure the outsole to the lasted shoe is sufficient to hold the outsole on the lasted shoe during the subsequent shoe making operations, but is not sufficient to act as a permanent fastening means for the outsole during wear.

20 The lasted shoe having the outsole temporarily secured thereto is then subjected to a stitching operation in which stitches 15, preferably lock stitches, are inserted through the lasting flange of the insole 7, the overdrawn margin of the upper 6, the marginal portion of the cover 10, and the outsole 13, preferably from a point back of the heel breast line on one side of the shoe to the corresponding point on the other side of the shoe.

30 As shown in Fig. 3 the sponge-rubber pad 12 depends from the cover. The peripheral edge of the pad 12 is not secured to the vertical side of the cup formed by the cover 10. As the cover 10 is secured to the insole 7 only along the vertical wall of the opening 9 the face 11 of the cover 10 bulges upwardly and thus maintains the pad normally in contact with the outsole only along the peripheral corner adjacent the bottom face of the pad and its peripheral edge. The pad 12 is secured neither to the insole nor to the outsole. The pad is thus free to accommodate itself independently of the insole and outsole to the varying conditions of use under the treading pressure of the wearer's foot transmitted to the pad through the cover. This feature, combined with the lock stitches which alone unite the upper, insole and outsole permanently, produces an extremely flexible shoe.

50 What is claimed as new, is:

1. A shoe characterized by an insole provided with an opening in its forepart, an outsole, a cover for the opening forming a cup having its edge interposed between the insole and the outsole, and a sponge-rubber pad depending from the cover into the cup, said pad being normally spaced from the vertical side of the cup.

2. A shoe characterized by an insole provided with an opening in its forepart, an outsole, a cover for the opening forming a cup having its edge interposed between the insole and the outsole, and a sponge-rubber pad depending from the cover into the cup unsecured to and normally spaced from the vertical side thereof.

65 3. A shoe characterized by an insole provided with an opening in its forepart, an outsole, a cover for the opening forming a cup having its edge interposed between the insole and the outsole, and a sponge-rubber pad depending from the cover into the cup unsecured to the outsole and normally spaced from the vertical side of the cup.

70 4. A shoe characterized by an insole provided with an opening in its forepart, an outsole, a cover for the opening forming a cup having its

edge interposed between the insole and the outsole, and a sponge-rubber pad depending from the cover into the cup unsecured either to the vertical side thereof or to the outsole, said pad also being normally spaced from the vertical side of the cup.

5 5. A shoe characterized by an insole provided with an opening in its forepart, an outsole, an upper having its marginal portion interposed between the insole and the outsole, a cover for the opening forming a cup having its edge interposed between the marginal portion of the upper and the outsole, a filling for the cup movable relatively to the vertical side thereof, and stitches inserted through the insole, the marginal portions of the upper and the cover, and the outsole.

10 6. A shoe characterized by an insole provided with an opening in its forepart, an outsole, an upper having its marginal portion interposed between the insole and the outsole, a cover for the opening forming a cup having its edge interposed between the marginal portion of the upper and the outsole, and filling for the cup normally spaced from and movable relatively to the vertical side thereof and unsecured to the outsole.

15 7. A shoe characterized by an insole provided with an opening in its forepart, an outsole, an upper having its marginal portion interposed between the insole and the outsole, a cover for the opening forming a cup having its edge interposed between the marginal portion of the upper and the outsole, and a sponge-rubber pad depending from the cover into the cup spaced from the vertical side thereof for movement relatively thereto.

20 8. A shoe characterized by an insole provided with an opening in its forepart, an outsole, an upper having its marginal portion interposed between the insole and the outsole, a cover for the opening forming a cup having its edge interposed between the marginal portion of the upper and the outsole, and a sponge-rubber pad having one face secured to that face of the cover unexposed to view in the finished shoe depending loosely into the cup normally spaced from the vertical side thereof.

25 9. A shoe characterized by an insole provided with an opening in its forepart, an outsole, an upper having its marginal portion interposed between the insole and the outsole, a cover for the opening forming a cup having its edge interposed between the marginal portion of the upper and the outsole, and a sponge-rubber pad having one face secured to that face of the cover unexposed to view in the finished shoe depending loosely into the cup normally spaced from the vertical side thereof and movable relatively to the outsole.

30 10. A shoe characterized by an insole provided with an opening in its forepart, an outsole, an upper having its marginal portion interposed between the insole and the outsole, a cover for the opening forming a cup having its edge interposed between the marginal portion of the upper and the outsole, and a sponge-rubber pad having one face secured to that face of the cover unexposed to view in the finished shoe depending loosely into the cup normally spaced from the vertical side thereof and movable relatively to both the insole and the outsole.

35 11. That improvement in the art of making shoes which consists in assembling an insole with a last and an upper, lasting the upper and securing it to the insole, removing a section bodily

from the forepart of the insole within the margin of the lasted upper, covering the aperture in the insole, placing a cushion on the cover, and thereafter attaching an outsole to the lasted shoe.

12. That improvement in the art of making shoes which consists in assembling an insole with a last and an upper, lasting the upper and securing it to the insole, removing a section bodily from the forepart of the insole within the margin of the lasted upper, covering the aperture in the insole, tucking the cover into engagement with the wall of the aperture, filling the cup formed by the tucked cover, and thereafter attaching an outsole to the lasted shoe.

13. A shoe characterized by an upper and an insole having an aperture in its forepart within the margin of the upper secured to the bottom of the insole, said aperture being covered by a piece of flexible material engaged with and secured both to the said margin of the upper and to the entire wall of the aperture, a piece of yieldable material smaller than the aperture having one face engaged with the unexposed face of the flexible material, and an outsole engaged both with the opposite face of the piece of yieldable material and with the margin of the flexible material secured to the said margin of the upper.

14. That improvement in the art of making shoes which consists in assembling an insole with a last and an upper, lasting the upper and

securing it to the insole, removing a section bodily from the forepart of the insole leaving an internal aperture therein, trimming the margin of the upper overdrawn upon the forepart of the insole to the edge of the aperture, rendering the 5 wall of the aperture adhesive, securing a cover comprising a piece of flexible material to the wall of the aperture by means that performs its securing function by engagement both with the cover and the entire face of the wall, placing 10 a filling within the cover, and thereafter attaching an outsole to the lasted shoe.

15. A shoe characterized by an insole provided with an aperture having a vertical wall in its forepart, a cover for the aperture secured to the 15 vertical wall thereof by means that performs its securing function by engagement both with the cover and the entire face of the vertical wall, and a cushion received within the cover.

16. A shoe characterized by an insole provided with an aperture in its forepart, a cover for the aperture having a sock lining engaging face secured to the wall of the aperture by means that performs its securing function by engagement both with said face of the cover and the entire 25 wall of the aperture, and a cushion received within the cover in engagement with the face thereof of opposite its sock lining engaging face.
